Inventors:

UNITED STATES PATENT OFFICE.

FRIEDRICH WILHELM VIETMEYER AND ALEXANDER VIETMEYER, OF PYRMONT, GERMANY.

BOTTLE-STOPPER.

No. 807,519.

Specification of Letters Patent.

Patented Dec. 19, 1905.

Application filed July 14, 1904. Serial No. 216,577.

To all whom it may concern:

Be it known that we, FRIEDRICH WILHELM VIETMEYER and ALEXANDER VIETMEYER, subjects of the German Emperor, residing at 5 Pyrmont, in the Empire of Germany, have invented a new and useful Bottle-Stopper, of which the following is a specification.

Our invention relates to improvements in bottle-stoppers whereby it is rendered possible to make them essentially of tin-plate and yet capable of withstanding a strong internal pressure in the bottles and remaining tight.

The objects of our improvement are, first, to so draw or otherwise form a conveniently-shaped tin-plate blank as to obtain a cap sufficiently stiff to withstand the bottle-pressure without bending and made integral with two or more pendent straight fingers reaching over the neck of the bottle; second, to provide the straight fingers with ribs by the drawing or forming process for the purpose of strengthening them; third, to sharply bend the ends of the straight ribbed fingers to form hooks bearing on the shoulder of the bottle-neck; fourth, to provide a pad or packing-disk of cork, india-rubber, or other material secured on the inside of the cap, and, fifth, in case the stopper is to be used over and over again to provide the neck of the bottle with 25 two or more faces or recesses for allowing the hooked ends of the stopper-fingers to pass through them, so that the bottle can be closed and opened by turning the stopper through a convenient angle. We attain these objects 30 by the stopper illustrated in the accompanying drawings, in which—

Figure 1 shows a blank of tin-plate for a stopper with two fingers. Fig. 2 is a top view of a stopper whose finger ends are not yet 40 bent. Fig. 3 is an elevation of the same. Fig. 4 is a side view of the same. Fig. 5 is a cross-section through the one finger of the stopper on the line $y z$ in Fig. 4. Fig. 6 is a vertical longitudinal section through a bottle-neck and the stopper secured thereon, the operation of closing the bottle being indicated by the dotted lines. Fig. 7 is a similar vertical section at right angles to that shown at Fig. 6. Fig. 8 is an elevation of a recessed 45 bottle-neck and the stopper adapted to be used over and over again. Fig. 9 is a top view of the recessed bottle-neck, and Fig. 10 shows a tin-plate blank for a stopper with three fingers.

Similar characters of reference refer to similar parts throughout the several views. 55

For producing a bottle-stopper with two fingers, as shown at Figs. 2 to 5, inclusive, a blank of tin-plate about of the shape shown at Fig. 1 is used. It is in any known manner 60 so drawn or otherwise formed that a spherically-shaped cap 1 and two straight ribbed fingers 2 2 are obtained. The cap 1 is sufficiently stiff and strong to resist the internal pressure in the bottle without bending. The 65 straight fingers 2 2 are subjected only to strains and not to any bending moment, and therefore they are strong enough for holding the cap 1 down on the bottle-neck. By the ribs 3 3 the fingers 2 2 are, moreover, stiffened. 70 A pad or packing-disk 4, of cork, india-rubber, or other material, is preferably secured on the inside of the cap 1 in any known manner. For instance, the cap 1 is shown as provided with two opposite teeth 5 5, which 75 engage in the pad or packing-disk 4. These teeth 5 5 may be formed by bending the two projections produced by the cuts 6 6 in the blank in Fig. 1.

The stopper described so far is put over the 80 neck 7 of a bottle and forced thereon in a suitable known machine—for instance, with the aid of a die 8. (Indicated by dotted lines at Fig. 6.) Then by means of two horizontally-guided movable parts 9 9 of the machine the 85 ends of the two ribbed fingers 2 2 are sharply bent around the lower edge of the neck 7. Thus two hooks 11 11 are formed, which bear against the shoulder 10 of the neck 7 and are sufficiently stiffened by the slightly-flattened ribs 12, Fig. 7, to resist the bending moment of the internal pressure of the bottle. 90

It is of special advantage that the cap 1 by reason of its spherical shape is sufficiently stiff to resist the action of the bottle-pressure 95 without bending and that the ribbed fingers 2 2 are not subjected to any bending moment, and therefore not liable to spreading out.

When it is desired to open the bottle, it is 100 only necessary to force outwardly either finger 2 to release it from the shoulder 10 of the neck, after which the stopper can be removed.

If the stopper is to be used over and over again, the neck 7 of the bottle is preferably 105 provided with two opposite recesses 13 13, (see Figs. 8 and 9,) which permit the hooks 11 11 to pass through. Then if the latter

- have been formed in the manner described above, and thereby the bottle closed, it is for opening of the bottle only necessary to turn the stopper through an angle of about ninety degrees until the hooks 11 11 engage in the recesses 13 13, and the stopper can be removed. It is obvious that for closing the bottle with an accomplished stopper the latter is so put over the neck 7 that the hooks 11 11 pass through the recesses 13 13, and then the stopper is turned through the proper angle. If necessary, the whole is placed in the machine to force the stopper downward, and either the stopper or the bottle alone is turned in a direction, or both may be simultaneously turned in opposite directions, until the hooks 11 11 engage with the shoulder 10 of the neck 7. Of course the recesses 13 13 may be replaced by faces.
- 20 The stopper may be provided with more than two fingers 2 2. Fig. 10 shows, for example, a blank from which a stopper with three fingers can be formed by drawing or otherwise.
- 25 This stopper can be produced quickly and cheaply and will be found to answer well for bottles containing liquids rich in carbonic acid.
- The stopper may be varied in its details 30 without deviating from the spirit of our invention. The neck of the bottle was hitherto assumed to be conical; but it may also be cylindrical, if so preferred.
- What we claim as our invention, and desire 35 to secure by Letters Patent, is—
1. In a stopper for bottles, the combination of a bottle provided with a projecting shoulder or the like, a cork, and a cap consisting of a main body portion seated on and overhanging the cork, said cap having integral pendent arms provided with hooked end portions for engaging the shoulder, said arms being longitudinally ribbed from their lower ends to a point adjacent the overhanging body portion 45 of the cap.

2. In a stopper for bottles, the combination of a bottle provided with a projecting shoulder or the like, a cork, a cap consisting of a main body portion seated on and overhanging the cork, said cap having integral pendent arms provided on their lower end with hooked portions for engagement with the shoulder, said arms joining the overhanging portion of the cap with a gradual curve providing greater width at their bases than at the ends of said arms, the said arms being longitudinally ribbed from their lower ends to a point above the bases thereof.

3. In a stopper for bottles, the combination of a bottle provided with an annular projecting shoulder recessed at two or more points, a cork or the like, a cap comprising a main body portion seated on and adapted to overhang the cork, said overhanging portion being provided with teeth securing the cork to the stopper, said cap also having integral pendent arms provided with hooked end portions, said arms being tapered toward their lower ends and joining the overhanging portion in a gradual curve, said arms being ribbed from their lower ends to a point adjacent the overhanging portion of the cap.

4. In a stopper for bottles, the combination of a bottle provided with a projecting shoulder recessed at two or more points, and a cap comprising a main body or cork-engaging portion, said cap having integral pendent arms provided with hook-shaped ends adapted for engagement with said shoulders, said arms being longitudinally ribbed throughout their length.

In testimony whereof we have signed our names to this specification in the presence of two subscribing witnesses.

FRIEDRICH WILHELM VIETMEYER.
ALEXANDER VIETMEYER.
